UNITED STATES PATENT OFFICE.

HENRY D. ALEXANDER AND HENRY C. WHITE, OF CANTON, OHIO.

SOFT-TREAD HORSESHOE.

SPECIFICATION forming part of Letters Patent No. 693,942, dated February 25, 1902.

Application filed December 23, 1901. Serial No. 86,875. (No model.)

To all whom it may concern:

Be it known that we, HENRY D. ALEXANDER and HENRY C. WHITE, citizens of the United States, residing at Canton, in the county of Stark and State of Ohio, have invented certain new and useful Improvements in Soft-Tread Horseshoes; and we do hereby declare that the following is a full, clear, and exact description of the same, reference being had to the annexed drawings, making a part of this specification, and to the figures of reference marked thereon, in which—

Figure 1 is a view showing the bottom or under side of the shoe. Fig. 2 is a sectional view showing in section the toe and heel calks. Fig. 3 is a view showing a portion of the shoe and the calks removed. Fig. 4 is a detached view of the toe-calk's retaining-bar. Fig. 5 is a detached view of one of the heel-calks' retaining-bars.

The present invention has relation to soft-tread horseshoes; and it consists in the novel construction hereinafter described, and particularly pointed out in the claim.

Similar numerals of reference indicate corresponding parts in all the figures of the drawings.

In the accompanying drawings, 1 represents the metal shoe, which is substantially of the form shown and of course is formed of metal. The toe and heel ends of the shoe are provided with sockets, the heel-sockets being formed by the flanges 2 and 3 and the toe-socket formed by the flanges 4 and 5, said flanges being located and arranged substantially as shown in the drawings.

The toe-calks 6 and the heel-calks 7 are formed of rubber or other elastic material and are of a size to give the proper amount of surface upon their bottom or under side, or, in other words, to produce a sufficient amount of contact-surface to produce a soft-tread shoe.

For the purpose of providing a means for attaching the toe and heel calks the metal plates 8 and 9 are provided, which metal plates are provided with screw-threaded apertures 10, which screw-threaded apertures are for the purpose of receiving the screws 11, said screws being located when placed in proper position

with reference to the shoe as illustrated in Fig. 2.

The metal plates 8 and 9 are each provided with the upward-extending lugs 12, which upward-extending lugs are so formed that when the plates 8 and 9 have been placed in proper position in the toe and heel calks and the rubber composing said calks properly vulcanized the upper ends of the lugs 12 will be flush with the upper faces of the calks 6 and 7. These lugs are located as above described for the purpose of producing a metal contact between the under face of the shoe 1 and the upper ends of the lugs 12, this construction being desirable to produce a rigid connection between the shoe and the calk-retaining plates 6 and at the same time providing for the proper cushion.

The inner ends of the heel-sockets are each provided with the cross-flanges 3 and the ends of the toe-calk sockets provided with the cross-flanges 5, which cross-flanges are formed of a material capable of bending, and are so formed for the purpose of being bent toward the ends of the calks to assist in holding said calks in proper relative position.

It will be understood that by our peculiar arrangement we are enabled to construct a shoe having the desired amount of cushion and yet at the same time provide a shoe the bottom or under side of which is formed to a great extent with a metal space, except at the points where the toe and heel calks are to be located.

It will be understood that in order to provide for the proper bending of the flanges 3 and 5 their ends should be somewhat tapered, as illustrated in Fig. 3, or the flanges 2 and 4 beveled at their ends. We have illustrated the flanges 3 and 5 tapered and also the flanges 2 and 4 beveled. This construction is preferable, owing to the fact that there can be no interfering with the edges of the metal used for the different calks and that the heel-flanges are free to be properly bent to securely hold the heel and toe calks.

Having fully described our invention, what we claim as new, and desire to secure by Letters Patent, is—

In a soft-tread horseshoe, a metal body or
shoe provided with calk-sockets at its heel and
toe ends, calks adapted to fit in the sockets and
provided with metal plates located in the body
5 of the calks and provided with integral lugs
extended flush with the upper faces of the
calks, and means for attaching the plates to
the metal shoe, substantially as and for the
purpose specified.

In testimony that we claim the above we 10
have hereunto subscribed our names in the
presence of two witnesses.

HENRY D. ALEXANDER.
HENRY C. WHITE.
